UNITED STATES PATENT OFFICE.

NICHOLAS V. D. BROCK, OF SANTA ANA, CALIFORNIA.

DESIGN FOR A DRAWER PULL.

Application filed October 9, 1926. Serial No. 19,285. Term of patent 3½ years.

To all whom it may concern:

Be it known that I, NICHOLAS V. D. BROCK, a citizen of the United States, residing at Santa Ana, in the county of Orange, State of California, have invented a new, original, and ornamental Design for a Drawer Pull, of which the following is a specification, reference being had to the accompanying drawing, forming a part thereof.

Figure 1 is a plan of the drawer pull, showing my new design.

Figure 2 is a front elevation of the drawer pull, showing my new design.

I claim:

An ornamental design for a drawer pull, as shown.

NICHOLAS V. D. BROCK.
